(57) **CLAIM**

The ornamental design for a closure for bags, as shown and described.

DESCRIPTION

FIG. 1 is a perspective view of a closure for bags showing our new design.

FIG. 2 is a top plan view thereof.

FIG. 3 is a bottom plan view thereof.

FIG. 4 is a left side elevational view thereof.

FIG. 5 is a right side elevational view thereof.

FIG. 6 is a rear elevational view thereof; and,

FIG. 7 is a front elevational view thereof.

In the drawings, the broken line showing portions of the closure depicts environment and forms no part of the claim.
